HOOK-THIMBLE COMBINATION
Ralph A. Ratcliff, 1300 Sunnyslope Ave.,
Belmont, Calif. 94002
Filed Oct. 11, 1965, Ser. No. 494,832
10 Claims. (Cl. 294—82)

This invention relates generally to a hook-thimble combination. More particularly this invention relates to a thimble member which is selectively receivable in engagement with the curved body portion of a hook member. Still more particularly this invention relates to a thimble which is employed in conjunction with a conventional hook to solve safety problems heretofore encountered with hooks of the type disclosed herein. In this connection, the combination of this invention is designed to strengthen a hook which forms part of the combination, to prevent damage to a load sustaining element engaged with the hook, and to prevent inadvertent disengagement of such a load sustaining element from operative engagement with the hook once such engagement is effected.

Hooks of the type disclosed herein are conventional stock items produced by various manufacturers, and such hooks are available in various sizes designed for accommodating loads of maximum known quantities. Such hooks are utilized in numerous ways, such as in conjunction with electrically actuated or manually actuated hoists and similar load sustaining devices. An illustrative utilization of such a hook in conjunction with a manually actuated hoist is illustrated in my Patent No. 2,967,046, dated Jan. 3, 1961. In that patent the hook construction shown is typical of standard hooks commonly employed before this invention.

While hereinafter reference is directed for illustrative purposes to use of this invention in conjunction with a hoist type load bearing device, applicability of this invention to other wide and varied uses in which hooks are commonly employed falls equally within the scope of this invention.

With conventional hooks of the type shown at the bottom of FIG. 3 of my aforementioned patent, it is common to engage a load supporting element, such as a flexible cable, directly with the hook body. This direct engagement with the hook usually results in an abrupt bend being formed in the cable which, not infrequently, produces one of two undesired and dangerous results, namely; (1) the cable is sharply distorted and the strands thereof may become broken due to the sharp bend imparted thereto, particularly after repeated use; and (2) because the cable is engaged with only a limited portion of the hook body, when heavy loads are supported by the cable the hook body may become distorted or bent from its conventional standard shape. In either case, release of the load supported by the hook can be an unwanted result.

The hook-thimble combination of this invention is designed to preserve such a load supporting cable from distortion and preclude breaking thereof, and also to distribute the load imparted to the hook body by the cable over a substantial portion of the hook body so that hook bending and other distortion is obviated.

From the foregoing it should be understood that objects of this invention include the provision of an improved hook-thimble combination having an extremely safe construction; the provision of a thimble member specifically designed to cooperate with a hook construction to preserve load supporting element engageable with

2

the hook and to prevent hook distortion by distributing stresses over a substantial portion of the hook body; the provision of a hook-thimble combination in which the thimble member additionally provides a safety gate 5 to preclude accidental separation of a load supporting element engaged with the thimble; the provision of a thimble member which is insertible into operative engagement with a hook body through the throat opening thereof in one position only so that accidental separation of the thimble from the hook body normally is precluded; and the provision in a hook-thimble safety combination of means for locking the thimble in one operative position; and the provision in a thimble member of a curved stress relieving saddle or seat with which a load 10 sustaining cable may be engaged without abrupt bending. These and other objects of this invention will become apparent from a study of the following description in which reference is directed to the appended drawings in which:

FIG. 1 is a side elevational view of the subject hook-thimble combination.

FIG. 2 is a front elevational view of the combination of FIG. 1.

FIG. 3 is a side elevational view, partly in section through the thimble taken in the plane of line 3—3 of FIG. 2.

FIG. 4 is a plan view of the thimble member of the subject combination.

FIG. 5 is a vertical sectional view through the thimble taken in the plane of line 5—5 of FIG. 4.

FIG. 6 is a view corresponding to FIG. 3 showing the mode of selective insertion of the thimble member into operative engagement with the hook body.

FIG. 7 is a side elevational view of the hook-thimble combination with the thimble oriented in an inverted operative position for a specific purpose.

FIGS. 8 and 9 are front and side elevational views respectively of a hook-thimble combination showing a modified thimble construction and means in conjunction therewith for locking the thimble against rotation from an operative position.

The combination of this invention, referring to FIGS. 1 and 2, comprises a hook member, generally designated 1, and a generally spool shaped thimble member, generally designated 2, operatively positioned within the area 45 lying between opposed portions of the hook and substantially filling such area. As mentioned previously, such a hook member has many and varied uses and one illustrative use is shown at the bottom of FIG. 3 of my aforementioned patent in which such hook is operatively engaged with a chain which passes through the housing of a hand operated hoist for sustaining a load engaged with the hook. To permit engagement of the hook with the chain in such an arrangement, as seen in FIGS. 1 and 2 of the attached drawings, the hook is provided with a shank portion 3 which terminates in a threaded upper end 4 on which is received a suitable lock nut 6, the purpose 50 of which is to retain a mounting clevis 7 pivotally engaged with the hook shank. It is to such clevis that the hoist chain is connected, as seen in FIG. 3 of said aforementioned patent.

The size of the thimble member is determined in accordance with the dimensions of the particular commercially available hook with which the thimble is to be used. It is envisioned that each such hook will have a specific thimble usable therewith, although under certain circumstances a given thimble may be effectively used with more than one size or style of hook.

Depending from the shank portion 3 of the hook is a curved body portion, generally designated 8, which terminates in an outwardly directed pointed end 9. Hook end 9 is spaced from the shank portion and a throat opening 11 is thereby provided between the hook and the shank portion. It is through throat opening 11 that the thimble member is selectively insertable and removable in a manner to be described. In this regard, it will be noted from FIG. 6 that the throat opening of a given hook is of a predetermined maximum lateral dimension D. Such dimension normally is standard for hooks of similar rated capacity and size, as are the other dimensions of the hook.

As perhaps best seen in FIGS. 3 and 6, the hook body portion has a curved internal surface, generally designated 12, which is generally circular in configuration for the major portion of its length extending between the shank portion and the hook end. It is this curved internal portion of the hook body portion with which the thimble member is intended to be closely engaged.

In the thimble embodiment shown in FIGS. 1 through 7, the thimble has generally the configuration of a spool which in side elevation has a generally circular outline. This thimble embodiment is defined by a central core portion 15 which extends between and interconnects laterally spaced flange portions 16 and 17. The flange portions cooperate to define a groove, generally designated 18, which extends around the periphery of core 15. As perhaps best seen in FIGS. 3 and 5, the core for the major portion of its periphery 19 is of curved configuration, the curvature of which is designed to correspond with the curvature of the internal surface 12 of the hook body portion. In the embodiment illustrated, the curvature of core periphery 19 is generally circular and thereby corresponds to the generally circular internal surface of the hook body portion. Thus the core substantially fills the internal area of the hook body when the thimble is located therein, as seen in FIG. 3.

To permit only selective insertion and removal of the thimble from the hook body, the generally circular core is provided with a flattened generally planar top portion 21. In this connection it should be understood that the maximum diameter of the circular portion of the core exceeds the predetermined dimension D of the hook throat opening so that insertion or removal of the thimble relative to the hook body is precluded in most orientations of the thimble. However, by providing the core with a planar top portion, the thimble is provided with a minimum dimension d between the flattened portion 21 of the core and the opposite curved portion 19 thereof. This core dimension d is only slightly less than the predetermined dimension D of the hook throat opening. Thus, by orienting the thimble as seen in FIG. 6 with the flattened core portion lying adjacent the hook end 9, the thimble may be moved through the throat opening without interference during insertion thereof into the hook body. Following such insertion, the thimble is rotated to its normal operative position shown in FIG. 3 so that the curved periphery 19 of the core is engaged with the correspondingly curved internal surface 12 of the hook body.

As seen in FIGS. 1 and 4, each of the respective flanges 16 and 17 of the thimble is provided with a pair of spaced ears 23, 24 and 26, 27. Depending upon the configuration and length of such ears, the thimble in side elevation will vary to a greater or lesser degree from a generally circular outline. Such ears impart a safety gate feature to the hook-thimble combination as will be described. However, the ears also restrict insertion of the thimble through the throat opening unless the thimble is oriented as shown in FIG. 6. That is, if it is attempted to insert the thimble when in the opposite orientation from that shown in FIG. 6, the ears on the respective flanges normally will engage with the shank portion of the hook and thereby preclude thimble insertion through the throat opening.

Formed in the thimble and projecting generally radially thereinto between the opposed ears on the respective flanges thereof is an opening, designated 31, through which a load supporting cable or like element may be inserted for engagement with the thimble. In the embodiment illustrated such opening is defined by a slot which extends generally radially into the thimble to and part way through the core from one margin of the thimble. It is through such slot that the load supporting cable, shown in dotted lines in FIGS. 1 and 2 and generally designated 32, is receivable.

As mentioned previously, in the absence of the thimble of this hook-thimble combination, load supporting cable 32 would normally be engaged directly with the curved internal portion 12 of the hook body. Because the hook body in transverse cross section is of relatively narrow construction, a cable engaged therewith would be abruptly bent and distorted by such hook body, thereby resulting in cable damage and ultimate breakage upon continued use. Also, in the absence of the thimble of this invention such a load supporting cable would engage only a limited portion of the hook body. When substantial loads are supported by the cable, such loads could distort and deform the hook body making the hook unusable, thus presenting extreme safety problems.

The thimble is provided in conjunction with the hook to preclude such abrupt bending and to insure stress distribution over a substantial portion of the hook body. To this end the thimble is provided with an enlarged saddle portion, generally designated 33, which extends transversely of the core and projects laterally in opposite directions beyond the confines of the flanges of the thimble, as best seen in FIG. 2. This saddle portion includes a pair of spaced ribs 34 which project from each associated flange as best seen in FIG. 4.

The top of the saddle portion defines a curved seat 36 which communicates directly with the base of the slot 31. Thus a load supporting cable inserted through the slot is directly engageable with the seat. As perhaps best seen in the dotted line showing of FIG. 2, seat 36 is gradually curved, has no abrupt bends therein, and preferably takes the form of an arc of a circle. Thus any chance of abrupt bending of and damage to a load supporting cable 32 engaged with the thimble is precluded because the thimble saddle seat increases appreciably the bending radius over which the cable passes. In this connection, slot 31 in the thimble and the curved seat with which the cable is engaged are formed in the thimble so that the cable 32 is suspended generally axially of the shank portion of the hook, as seen in FIG. 1, when the thimble is properly oriented. Thus, the direction of pull imparted to the hook by the cable remains centered regardless of the direction of strain applied.

As mentioned previously, the thimble also provides the additional important advantage of providing a safety gate for the hook by blocking the throat opening when the thimble is properly oriented. Thus inadvertent separation of the cable from operative engagement with the hook-thimble combination may be precluded. That is, the thimble provides a safety gate which blocks the throat opening when the thimble is in the position shown in FIGS. 1 and 3. This safety gate blocking function is performed by the ears 24 and 27 on the opposed flanges 16 and 17 as should be apparent from FIGS. 1 and 3. In this connection, referring to FIGS. 8 and 9, by lengthening the ears on the flanges, so that they take the appearance indicated by ears 23', 24' and 26', 27' of the modification of FIGS. 8 and 9, the throat opening may be even more completely blocked.

While normally the thimble will remain in the preferred operative position shown in FIGS. 1 and 2 without assistance, under certain operating circumstances it may be desired to positively preclude rotation of the thimble in the hook body, and means may be provided for positively locking the thimble against such rotation. One simple locking means for that purpose has been shown in FIGS. 8 and 9 and comprises a locking member, which in the

embodiment illustrated is defined by a length of wire 41, which is projected through spaced holes 42 and 43 provided in each of the flanges 16 and 17 of the thimble. The ends of wire locking member are then brought together and twisted to secure the same in place. Thus, the wire locking member extends across the throat opening, as best seen in FIG. 8, in close proximity to the shank portion 3 and the end 9 of the hook. Any attempt thereafter to rotate the thimble is positively precluded by engagement of the wire locking member with the hook shank 3 or hook end 9.

In those situations in which the hook size is sufficiently large to permit engagement of a load supporting cable 32 directly with the hook without encountering the safety problems mentioned previously, the thimble of this invention may perform solely a safety gate function when oriented as seen in FIG. 7. That is, by rotating the thimble from its preferred operative position, in which the cable receiving slot 31 extends generally upwardly in alignment with the hook shank portion, to the inverted position seen in FIG. 7, the cable may be freed from engagement with the thimble saddle portion and may drop into engagement directly with the curved internal surface 12 of the hook body. In this arrangement the thimble completely blocks the throat opening and serves solely as a safety gate. Under most circumstances, however, the thimble would be employed for the dual safety purposes mentioned previously.

While hereinbefore reference has been directed to use of a flexible cable load supporting element in conjunction with the thimble, it should be understood that other suitable load supporting elements also are usable with this invention and will receive the advantages produced thereby when so used.

Having thus made a full disclosure of this invention, reference is directed to the appended claims for the scope to be afforded thereto.

I claim:

1. A hook-thimble combination, comprising
  - (A) a hook defined by
    - (1) a shank portion, and
    - (2) a curved body portion terminating in an end spaced from said shank portion and defining a throat opening therewith, and
  - (B) a thimble positioned within said hook body portion, said thimble having
    - (1) an opening therein, the base of which provides a seat for a load supporting element to be engaged with said thimble,
    - (2) a central core, a portion of the periphery of which corresponds generally with the configuration of an inner surface of the body portion of said hook along the bottom thereof, whereby stresses imparted to said thimble upon engagement of said load supporting element with said thimble are distributed by said thimble over a substantial portion of said hook body portion,
    - (3) a saddle portion extending transversely of said core and projecting laterally in opposite directions from said thimble,
    - (4) the upper surface of said saddle portion defining said seat at the base of said opening which is curved and free of abrupt bends, so that abrupt bending of said load supporting element engaged with said thimble, and resultant damage thereto, is precluded by said thimble.
2. The thimble of the combination of claim 1 in which
  - (5) said seat defined by the upper surface of said saddle portion defines substantially an arc of a circle,
  - (6) the center of such arc lying generally in line with the axis of the shank portion of said hook when said thimble is operatively positioned with said hook body portion.

3. The thimble of the combination of claim 1 in which
  - (5) said thimble opening comprises a slot which extends generally radially into said thimble to and partially through said core from one margin of said thimble, and which further includes
    - (6) means blocking said throat opening to preclude removal of said load supporting element from engagement with said saddle portion when said thimble is oriented with said slot opening upwardly in general alignment with said hook shank portion.
  4. The thimble of the combination of claim 1 in which
    - (5) said thimble core has a configuration which permits sliding insertion and removal of said thimble through said throat opening when said thimble is arranged in one particular orientation but which precludes such insertion and removal in orientations other than such one orientation,
      - (a) said core being generally circular in cross-section and having a flattened portion along one margin thereof,
      - (b) said flattened portion reducing the dimension of said core in one direction to less than the dimension of said hook throat opening so that said thimble may be slidably inserted through said throat opening when said thimble is arranged in said one orientation.
  5. The thimble of the combination of claim 1 which further includes
    - (5) a pair of flange portions provided on opposite sides of said core,
    - (6) said flange portions being engaged with outer side surfaces of said hook body portion and thereby precluding lateral shifting of said thimble,
    - (7) said saddle portion and the seat defined by the upper surface thereof projecting laterally beyond said flange portions.
  6. The thimble of the combination of claim 3 in which said throat blocking means of said thimble comprises
    - (7) an enlarged ear provided on said thimble which extends in a direction generally away from said seat of said saddle portion so that it may lie across said throat opening of said hook.
  7. The thimble of the combination of claim 6 which further includes
    - (8) means for locking said thimble in said position with said ear lying across said throat opening.
  8. The hook-thimble combination of claim 3 in which said throat blocking means of said thimble comprises
    - (7) enlarged ears extending from each of two spaced flanges provided on opposite sides of said core,
    - (8) one such ear being provided on each side of said thimble slot on each of said flanges, and in which said combination includes locking means comprising
    - (9) a rotation preventing member extending across said throat opening and secured between each pair of said spaced ears so as to be engageable with said hook shank portion and said hook end upon attempted rotation of said thimble to positively preclude such rotation.
  9. For use in combination with a hook which is defined by a shank portion and a curved body portion which terminates in an end spaced from said shank portion and defines a throat opening therewith,
    - (A) a thimble receivable through said throat opening of such hook and positionable within said body portion thereof, said thimble comprising
      - (1) a generally spool shaped peripherally grooved body having a central core and flanges at opposite ends of said core,
      - (2) said core having a maximum dimension which normally precludes insertion thereof through said hook throat opening and a minimum dimension which permits such insertion,
      - (3) a slot opening extending generally radially

- into said thimble from a margin thereof into said core, and
- (4) an enlarged saddle portion extending transversely of said core and projecting laterally beyond said core flanges,
- (5) the base of said slot defining the upper surface of said saddle portion,
- (6) said saddle portion upper surface providing an enlarged curved seat over which a load sustaining member is engageable with said thimble without abrupt bending thereof.
10. The thimble of claim 9 which includes
- (7) means for blocking said throat opening of said hook

5

10

when said thimble is oriented within said hook body portion with said slot opening extending generally in line with said hook shank portion.
